A. RUSH,
DOOR FOR ELEVATOR SHAFTS,
APPLICATION FILED JUNE 21, 1919.

1,315,795.

Patented Sept. 9, 1919.

UNITED STATES PATENT OFFICE.

ALBERT RUSH, OF COLUMBUS, OHIO.

DOOR FOR ELEVATOR-SHAFTS.

1,315,795.

Specification of Letters Patent. Patented Sept. 9, 1919.

Application filed June 21, 1919. Serial No. 305,889.

To all whom it may concern:

Be it known that I, ALBERT RUSH, a citizen of the United States, residing at Columbus, in the county of Franklin and State of 5 Ohio, have invented a certain new and useful Improvement in Doors for Elevator-Shafts, of which the following is a specification.

The invention relating to elevator doors 10 or gates has for its object to provide an improved construction whereby a vertically sliding door or gate can be made practically the full height of the doorway or carriage entrance.

15 The invention is embodied in the example herein shown and described, the features of novelty being finally claimed.

In the accompanying drawing—

Figure 1 is mainly a vertical sectional view showing three floors of a building equipped with the invention.

Fig. 2 is a similar section on a larger scale with the door and parts broken out to illustrate details of construction.

25 Fig. 3 is a horizontal section on the line II—II, Fig. 2, to illustrate the details of construction of the door guide or channel and the engagement of the door therewith.

Fig. 4 is a side and sectional detail view 30 like Fig. 2 showing means for bridging the gap between the channel on the building and that on the car.

In the views 5 designates the several floors of a building adjacent the elevator shaft, 35 and 6 the opening or doorway to the shaft. Each opening 6 is provided at the opposite sides thereof with parallel vertical channels like that shown at 7, said channels being deflected or inclined at their upper portions 40 beyond the opening 6 as at 7^a inward toward the shaft.

8 designates the several doors at the floors in the building. Each door is provided near its lower corners with laterally projecting stud shafts 9 containing antifriction rollers 10 that travel in or engage the channels 7, 7^a. Said doors are also provided near their upper corners with similar rollers 11 that engage said channels. Each door 50 has secured to it near each of the lower corners short bent arms 12 to which are connected chains 13, said chains being passed up over sheaves 14. Said chains 13 are provided with counter weights 15 to counter- 55 balance the door and render it easy to raise and lower.

16 designates the elevator car or carriage, the same to be equipped with the usual or any suitable hoisting apparatus (not shown) for raising and lowering it in the shaft or 60 well. In the present instance the top of the car is equipped with a suitable frame 17, said frame including a pair of inclined channels 18 forming a support and guiding means for the door, the mouths to said channels at the lower ends being enlarged. The inclination of the channels 18 is such that when the car is stopped in that position where the floor of the car coincides with a floor of the building the 65 mouths of the channels 18 coincide with the exits or upper ends of the channels 7, 7^a as shown in Figs. 1 and 2. Any gap between the lower sides of the mouths of the channels 18 and the exits of the channels 7, 7^a 70 can be bridged by short lever-like track sections 19 pivoted to channels 7, 7^a as at 20 (see Fig. 4) so as to avoid undue noise or clatter when the door is being raised. When the door is lowered the rollers 11 press upon 80 the short arms 19^a of said track sections 19 and hold them in raised position as indicated by broken lines Fig. 4. When the door is raised said track sections 19 fall to operative 85 position as shown in full lines Fig. 4.

In practice, therefore, when the car is stopped at a floor the door is raised by hand or otherwise and deflected by the upper walls of the channel portion 7^a into the channels 18 on top of the car thereby leaving 90 the doorway entirely clear for the passage of persons or freight from the car to the floor or reversely. When the door is thus raised the rollers 11 travel from the channels 7 and 7^a into the channels 18. It will, of 95 course, be necessary to lower the door completely before the car can be moved away to another floor, but this requirement promotes the safety of persons using the car.

Changes can be made in the forms of the 100 parts without departing from the gist of the invention claimed.

What I claim is—

1. The combination with a building having an elevator shaft and doorways leading 105 from the floors of the building to the shaft and a car to move vertically in said shaft, of sliding doors for the doorways, and a support on the car to receive a door when it is raised to open a doorway.

2. The combination with a building having an elevator shaft, doorways leading 110

from the floors of the building to the shaft and a car to move in said shaft, doors for said doorways, guiding means on the doorways for guiding said doors vertically and 5 guides mounted on the top of the car to receive a door when the same is raised to open the doorway.

3. The combination with a building having an elevator shaft, doorways leading 10 from the floors of the building to the shaft and a car to move in said shaft, vertically sliding doors for said doorways and guides mounted on the top of the car to receive a door when the same is raised to open the 15 doorway.

4. The combination with a building having an elevator shaft, doorways leading from the floors of the building to the shaft, and a car to move in said shaft, vertically 20 sliding doors for said doorways, a support on the top of the car to receive a door when raised, and deflecting means for guiding the door onto said support.

5. In combination, a car, a doorway past 25 which the car moves, a door for the doorway, means on the car for receiving the door, and guiding means for directing the door when moved from the car to close the doorway and from the doorway to the car 30 when the door is to be opened.

6. The combination with a building having an elevator shaft, doorways leading from the floors of the building to the shaft, a car to move in said shaft, doors for said 35 doorways, guiding means on the doorways for guiding said doors vertically, guides mounted on the top of the car to receive a door when the same is raised to open the doorway and movable track sections for 40 bridging the gaps between the guiding means on the doorway and the guides on the top of the car.

7. The combination with a building having an elevator shaft, doorways leading from 45 the floors of the building to the shaft, a car to move in said shaft, doors for said doorways, guiding means on the doorways for guiding said doors vertically, guides mounted on the top of the car to receive a door when the same is raised to open the doorway and movable track sections for bridging the gaps between the guiding means on the doorway and the guides on the top of the car, and means on the door for moving said 50 movable track sections out of operative position when the door is lowered.

8. The combination with a building having an elevator shaft, doorways leading from the floors of the building to the shaft, a car to move in said shaft, doors for said 60 doorways, guiding means on the doorways for guiding said doors vertically, guides mounted on the top of the car to receive a door when the same is raised to open the doorway and pivoted track sections for 65 bridging the gaps between the guiding means on the doorway and the guides on the top of the car.

9. The combination with a building having an elevator shaft, doorways leading 70 from the floors of the building to the shaft, a car to move in said shaft, doors for said doorways, guiding means on the doorways for guiding said doors vertically, guides mounted on the top of the car to receive a 75 door when the same is raised to open the doorway and pivoted track sections for bridging the gaps between the guiding means on the doorway and the guides on the top of the car, and means on the door for 80 moving said pivoted track sections out of operative position when the door is lowered.

ALBERT RUSH.
